Robert M. Zacharias ATTORNEY.

UNITED STATES PATENT OFFICE.

SAMUEL A. VAN OSDEL, OF JOHNSON, NEBRASKA.

TONSILLOTOME.

1,361,649.

Specification of Letters Patent.

Patented Dec. 7, 1920.

Application filed May 5, 1920. Serial No. 379,032.

To all whom it may concern:

Be it known that I, SAMUEL A. VAN OSDEL, a citizen of the United States, and a resident of Johnson, county of Nemaha, State of Nebraska, have invented certain new and useful Improvements in Tonsillotomes, of which the following is a specification.

This invention relates to surgical instruments for the removal of portions of tonsils or other relatively inaccessible parts and has for one of its objects the provision of an instrument of this class which will have a powerful crushing action and a distinct cutting action and can be readily and effectively operated by one hand. A further object of the invention is the provision of such an instrument which is of simple construction, which may be readily disassembled or assembled and which can be operated with a minimum of inconvenience to the patient.

Further objects of the invention and the features of novelty will be apparent from the following specification when taken in connection with the accompanying drawings, in which:

Figure 1 is a side elevation of an instrument embodying my invention.

Fig. 2 is a fragmentary vertical section 30 of the instrument shown in Fig. 1, but showing the parts in another position.

Fig. 3 is a transverse vertical section on line 3—3 of Fig. 2.

Fig. 4 is a fragmentary enlarged longitudinal section of the forward end of the instrument.

Fig. 5 is a plan view of the instrument showing the operating members in retracted position, and

Fig. 6 is an enlarged vertical cross section 40 on the line 6—6 of Fig. 4.

Referring to the drawings, the present embodiment of my invention comprises a base or frame member 11, having a handle 12 rigidly depending therefrom, and preferably integral therewith. The main portion of the frame is slender and its forward end is widened as shown in Fig. 5 and provided with a fenestrum 13 to receive the member which is to be severed. The top of the frame 11 is flat except at its forward end where it is formed with a guide flange 14 which projects upwardly from the widened portion of the frame and is turned inwardly 55 to provide means for guiding a hemostat blade 15 and a cutting blade 16. The guide

flange 14 is continued around the end of the instrument as shown in Fig. 5, being preferably so formed as to overlie the end of the hemostat blade 15 when it is in its extreme forward position, and its inwardly directed portion is preferably narrower adjacent the fenestrum, as shown at 17 to more readily receive the part to be severed.

The hemostat blade 15 is preferably of the same width as the main frame 11 and is widened at its forward end to fit in the flanged portion of the frame. The end of the blade is rounded to correspond with that surface of the frame with which it cooperates in its extreme forward position, and the rear portion of the blade is thickened and has a recess 18 in its lower side to receive an arm 19 of an operating lever 20 which is pivotally carried by the frame 70 so as to swing to and from the handle 12. A pivot member 21 extends transversely through the arm 19 and the thickened portion of the hemostat blade 15, and has a portion thereof which is extended forwardly 80 and then curved over the hemostat blade 15, the end of the curved portion having a projection 22 thereon which springs into a recess 23 in the hemostat blade. The pivot member 21 is thus secured in place and may 85 be readily removed to permit disassembly of the parts of the instrument by springing the projection 22 out of the recess 23 and swinging the member until it may be withdrawn laterally.

The cutting blade 16 is flat and corresponds in shape to the top surface of the frame, being widened at its forward end to fit between the side portions of the guide flange 14 of the frame. The end of the blade is rounded to conform to the shape of the forward edge of the frame 11, a slot 16^a being formed in the frame 11 into which the cutting blade extends when in its extreme forward position, and a cutting edge is 95 formed at the lower surface of the cutting blade 16 by beveling the end of the blade away from the hemostat blade 15 for a purpose which will be described hereafter. A rigid projection 24 extends downwardly 100 from the rear end of the cutting blade 16 to facilitate reciprocation of the blade, the forward motion of the blade being limited by the engagement of the projection 24 with the frame 11, and the rear portion of the 110 blade is slotted as shown at 25 to receive the arm 19 of the operating lever 20.

The operating lever 20 is formed with circular oppositely projecting bearing portions 26 which are received in open slots 27 in the sides of the frame 11 adjacent the handle 12, and a spring 28 is provided for normally holding the lever 20 away from the handle. This spring 28 is preferably detachably secured to the lever 20, a T-shaped projection 29 being provided on the lever and an elongated slot 30 being formed in the spring, so that the spring may be placed in position on the projection and rotated to the operative position shown. At its upper end the spring is slightly curved and frictionally engages a curved surface 31 in the handle 12. As the operating lever 20 is moved toward the handle 12 it tends to rotate about the point of engagement of the spring 28 with the surface 31, and the bearing portions 26 will tend to roll on the rear surfaces of the slots 27 from the full line position shown in Fig. 1 to a position lower than that shown in dotted lines in Fig. 2. By reason of the frictional engagement of the spring with the surface 31, the lever 20 and the operating blades 15 and 16 are resiliently held in their lowermost position throughout the forward movement of the blades.

30. A latch 32 is pivotally mounted in a slot 33 in the handle 12 on transversely extending pin 34 and is provided with teeth 35, for engagement with a tooth 36 on the end of the operating lever 20. A spring 37 is mounted in a slot 38 in the handle 12 and is held in place by webs 39 which project inwardly from the sides of the slot 38. The end of the spring 37 is slightly curved and is received in a slot 40 in the latch 32, the slot being sufficiently wide to permit the latch to be swung out of engagement with the spring, and the end of the latch is rounded as shown at 41 to engage the curved end of the spring and force it away from the handle sufficiently to permit the latch to be swung back to operative position.

In use the instrument is grasped in either hand with the fingers engaging the operating handle 20, the parts being in the position shown in Fig. 1. When the instrument is in proper position relative to the tonsil or other part to be severed, the hemostat bar is forced forward with a powerful crushing action by gripping the handle 12 and lever 20, the forward end of the bar co-operating with the frame at the forward end of the fenestrum to crush and practically sever the tonsil. The cutting blade 16 is carried forward by the engagement of the arm 19 at 50 the forward edge of the slot 25, the extent of its movement being almost as great as that of the blade 15. The cutting blade 16 is then forced forward through the rest of its stroke by engaging the thumb of the hand holding the instrument with the pro-

jection 24, to sever the crushed member. It will be apparent that in this operation the beveled surface of the cutting blade 16 will engage the surface of the crushed stump and will have a further crushing and hemostatic action.

The instrument comprises but few parts, and these are of simple construction and can be readily disassembled for cleaning and sterilization. It provides for powerful and effective crushing action which, together with the cutting operation, is accomplished without the use of the other hand, thus obviating the danger of the instrument slipping or twisting with consequent injury to the patient. The operation of the instrument does not necessitate moving any part of the hand in such a way as to obstruct the view of the operator, and the relatively sliding parts are so constructed as to operate without unnecessarily inconveniencing the patient.

While I have shown and described one embodiment of my invention, it will be understood that changes may be made in the details of construction without departing from the spirit of the invention which is defined in the appended claims.

Having thus described my invention, what I claim is:—

1. A surgical instrument, comprising a frame member and a handle therefor, a hemostat member carried by said frame, a cutting member carried by said frame for free sliding movement relative to said hemostat member, means operable by gripping movement of the hand engaging said handle for reciprocating said secondary co-operating member, and means for independently reciprocating said cutting member.

2. A surgical instrument comprising a frame member and a handle therefor, a member pivoted for swinging movement toward and from said handle, a cutting member carried by said frame, a secondary co-operating member carried by said frame, said pivoted member co-operating with said secondary co-operating member to reciprocate it relatively to said frame, and means operable by the hand engaging said handle for reciprocating said cutting blade.

3. A surgical instrument comprising a frame, a handle member rigid therewith, a second handle member movable toward and from said first mentioned handle member, a crushing member carried by said frame, a cutting member carried by said frame and slideable freely relative to said crushing member, said movable handle member co-operating with said crushing member to reciprocate it, and a rigid extension on said cutting member for engagement by the thumb of the hand engaging said handle members.

4. A surgical instrument comprising a

- frame having an abutment thereon, a handle for said frame, a hemostat blade slidably carried by said frame for coöperation with said abutment, a cutting blade carried by 5 said frame, means for reciprocating said cutting blade, and a lever fulcrumed for motion to and from said handle and pivotally connected to said hemostat blade.
5. A surgical instrument comprising a 10 frame having a handle projecting therefrom and having an abutment thereon, a hemostat blade and a cutting blade slidably carried by said frame, each of said blades having a portion arranged to coöperate with 15 said abutment, means for reciprocating said cutting blade, and a member having a pin and slot pivotal connection with said handle and having an arm coöperating with said hemostat blade to reciprocate it.
- 20 6. A surgical instrument comprising a frame having an abutment thereon, a crushing member and a cutting member slidably carried by said frame, means for independently reciprocating said members to move 25 portions thereof into coöperative relation with said abutment, said cutting member being beveled to form a cutting edge at that side thereof remote from the crushing member.
- 30 7. A surgical instrument comprising a frame, a crushing member and a cutting member carried by said frame and freely slideable relative thereto, means for reciprocating said cutting member, a handle member 35 rigid with the frame, a second handle member movable toward and from said first mentioned handle member and coöperating with said crushing member to reciprocate it
- relative to the frame, and a latch member carried by one of said handle members and 40 coöperating with the other handle member to prevent retraction of said crushing member.
8. A surgical instrument comprising a frame having a forwardly projecting portion 45 and a handle portion projecting therefrom, a cutting member carried by said frame, a secondary coöperating member carried by said frame, means for reciprocating said cutting member, means for reciprocating said secondary coöperating member comprising a member movable relative to the handle portion of said frame and having an arm connected to said secondary coöperating member, and resilient means opposing motion of said movable member toward said handle portion and coöperating with said movable member and said frame to hold said secondary coöperating member toward said frame. 50 55 60
9. A surgical instrument comprising a frame, a cutting blade slidably mounted on said frame, a secondary coöperating member carried by said frame, means for reciprocating said cutting member, an operating member movable relative to said frame to reciprocate said secondary coöperating member and having an arm projecting through 65 said frame and said cutting member, and a removable member connecting said arm 70 and said secondary coöperating member to hold said frame, said cutting member and said secondary coöperating member in assembled relation.

In testimony whereof I affix my signature. 75
SAMUEL A. VAN OSDEL.
